UNITED STATES PATENT OFFICE.

JOHN B. PRENDERGAST AND HANS TALLAKSON, OF WEBSTER, DAKOTA TERRITORY.

STRAW-BURNING COOKING-STOVE.

SPECIFICATION forming part of Letters Patent No. 394,997, dated December 25, 1888.

Application filed January 31, 1888. Serial No. 262,536. (No model.)

To all whom it may concern:

Be it known that we, JOHN B. PRENDERGAST and HANS TALLAKSON, citizens of the United States, residing at Webster, in the county 5 of Day, Territory of Dakota, have invented certain new and useful Improvements in Straw-Burning Cooking-Stoves, of which the following is a specification, reference being had therein to the accompanying drawings.

This invention has relation to straw-burning cooking-stoves, and among the objects in view are to provide a stove for this purpose which will be cheap and simple, so arranged as to utilize to the best advantage the heat 15 generated therein for cooking purposes, and to provide means for feeding fuel in a compact and convenient manner to the stove.

Other objects and advantages of the invention will hereinafter appear, and the novel 20 features be particularly pointed out in the claims.

Referring to the drawings, Figure 1 is a substantially central longitudinal section of a straw-burning cooking-stove constructed in 25 accordance with our invention, the fuel-cylinder being contained therein and in the act of feeding fuel thereto, and Fig. 2 is a perspective, in detail, of the fuel-cylinder.

Like letters indicate like parts in both the 30 figures of the drawings.

A represents the fire-box of the stove, which is cylindrical and formed of light metal, and is provided with an ash-pit, A', at its front end, having an ash-pan, A², and an intermediate grate, A³, mounted between the fire-cylinder and the ash-pit. The ash-pit A' serves 35 to support the front end of the cylinder A, and in this instance suitable legs, A⁴, serve to support the rear end thereof.

The cylinder A is provided with doors A⁵ A⁶ at its front and rear ends, respectively, and at the former end with a draft-opening, A⁷. A partition, A⁸, is arranged horizontally 40 within the cylinder, and serves to conduct the products of combustion to the front and along the upper portion and to the rear of the cylinder thus under the openings A⁹, formed in the top of the cylinder for the reception of ordinary culinary vessels placed thereon.

At the rear end of the partition A⁸ there is 45 formed an opening, A¹⁰, adapted to be closed

and opened by means of a sliding gate or damper, A¹¹, mounted on the partition and controlled by an operating-rod, A¹², which projects from the front of the stove. 55

At the rear end of the cylinder A is formed an opening, A¹³, upon which is fitted the pipe or uptake B, which is formed with a heating-drum, B', containing an oven, B², around which the heat passes on its way up said pipe. 60

C represents the feeding-cylinder, which is open at both ends and formed with opposite longitudinal slots, C', through which pass a cross-bar, C², which projects at each side of the cylinder, and has secured thereto and 65 within the cylinder a circular plate, C³, adapted to ride from end to end of the cylinder. 60

To feed fuel to the fire-cylinder A, the fuel-cylinder C is first filled with fuel and introduced through the door A⁶ into said fire-cylinder, and the ends of the bar C² inserted into oppositely-arranged hooks A¹⁴, (see dotted lines, Fig. 1,) and the cylinder then withdrawn by means of the cross-bar C⁴. As the cylinder is withdrawn to the rear the bar C² and its plate C³ are held stationary by means of the hook A¹⁴, arranged at each side of the door A⁶, which plate prevents the fuel from being withdrawn with the cylinder, and forces 80 the same to remain within the fire-cylinder A. When the cylinder C is withdrawn as far as permissible, the rod C² is disengaged from the hook A¹⁴ and the cylinder C wholly removed from the stove, and can be again refilled. The 85 door A⁶ is then closed and the stove will be in condition for cooking. By closing the opening A¹⁰ by means of the damper A¹¹ and its rod A¹², a more indirect draft is given to the stove, and the products of combustion carried 90 under the openings A⁹, as before indicated. By drawing the damper A¹¹ to the front, a direct draft is given, and the heat carried directly around the oven B² for baking purposes. 95

Having described our invention, what we claim is—

1. In a straw-burning cooking-stove, the combination of a fire-cylinder having an opening at one end provided with oppositely-arranged hooks, with a fuel-cylinder longitudinally slotted on opposite sides, a cross-bar 100

projecting through and adapted to ride in said slots and to be connected with said hooks, and a follower-plate mounted upon said cross-bar, substantially as specified.

5 2. The cylinder A, provided with openings at its ends, in combination with the cylinder C, longitudinally slotted, as at C', having the cross-bar C², mounted in the slot, and plates C³, mounted on said bar, substantially as specified.

10 3. The combination of the cylinder A, having the doors A⁵ A⁶ and the oppositely-arranged hooks A¹⁴, with the cylinder C, oppo-

sitely slotted, as at C', and having the cross-bar C², mounted in the slots and provided with a plate, C³, and the bar C⁴, secured to the mouth of said cylinder, substantially as specified. 15

In testimony whereof we affix our signatures in presence of two witnesses.

JOHN B. PRENDERGAST.
HANS TALLAKSON.
